UNITED STATES PATENT OFFICE.

JOSEPH A. McDONALD, OF AUBURNDALE, AND WILLIAM R. FORSYTH, OF SWAMPSOFT, MASSACHUSETTS; SAID McDONALD ASSIGNOR, BY MESNE ASSIGNMENTS, OF HIS RIGHT TO UNITED SHOE MACHINERY CORPORATION, OF PATERSON, NEW JERSEY, A CORPORATION OF NEW JERSEY.

VENeer-PRESS.

1,315,976.

Specification of Letters Patent. Patented Sept. 16, 1919.

Application filed April 30, 1915. Serial No. 25,060.

To all whom it may concern:

Be it known that we, JOSEPH A. McDONALD and WILLIAM R. FORSYTH, citizens of the United States, residing at Auburndale, 5 in the county of Middlesex, and Swampscott, in the county of Essex, and State of Massachusetts, respectively, have invented certain Improvements in Veneer-Presses, of which the following description, in connection with the accompanying drawings, is 10 a specification, like reference characters on the drawings indicating like parts in the several figures.

This invention relates to presses and is 15 herein illustrated in connection with a veneer press for use in the manufacture of boots and shoes.

In the manufacture of McKay shoes it is customary to cement to the inner surface 20 of the forepart of a sole a tap the rear end of which is skived. Hitherto it has been the practice to lay the cemented taps upon the cemented soles, then to pile the veneered soles in a press, and finally to exert positive 25 pressure upon the pile by means of a screw. Ordinarily from ten to twelve hours are required for the drying and setting of the cement; and from this fact two disadvantages result: First, a large number of presses 30 are required, and second, inasmuch as the pile of soles shrinks during the drying process, it is necessary to tighten the screws of the presses at frequent intervals in order 35 to maintain sufficient pressure.

According to one feature of the present invention pressure is applied to the pile of blanks through a spring which is thereby compressed, and means are provided for holding the spring compressed after the 40 pressure is withdrawn. In the illustrative device there is provided a holder having a support for the pile of blanks which rests upon a spring, a clamping member slidable on the holder toward the support, and a one-way clutch connecting the clamping member and holder. With such a construction 45 a pile of veneered soles may be assembled in the holder, the holder placed in the press, pressure applied upon the movable end or 50 clamp to force the soles together and at the same time to compress the spring which supports the other end or clamp member. When sufficient pressure has been applied

the adjustable clamp member is locked in position; and the holder may then be removed from the press and placed aside without further attention, the compressed spring serving to maintain sufficient pressure upon the soles during the drying operation. Thus, by providing a large number 55 of holders, comparatively few presses will be required.

These and other features of the invention including certain details of construction and combinations of parts will be described in connection with an illustrative machine and 60 pointed out in the appended claims.

Referring now to the accompanying drawings,—

Figure 1 is a perspective of a machine in which the present invention is embodied;

Fig. 2 is a fragmentary sectional view showing more particularly the relation of the double pawl to the rack bar;

Fig. 3 is a similar view showing more particularly the relation of the operating pawl to the rack bar;

Fig. 4 is a similar view of the holder showing the means for locking the clamping member in position.

The press, as distinguished from the holder, comprises a base 1, two uprights 3 and a cross-piece 5. Bolted to the under side of the cross-piece is a box 7 having an upwardly extending projection provided with a square 85 passageway to receive a rack-bar 9, said rack-bar being formed on two contiguous sides with series of teeth 11 and 13. At its lower end the rack-bar is connected by a ball and socket joint with a presser 15 90 which is adapted to contact with the clamping member of the holder as will presently be described. An operating lever 17, pivoted at 19 to the box 7 has a cylindrical socket to receive the cylindrical hub of an 95 operating pawl 21, a spring 23 serving to urge said pawl at all times toward the rack-bar. In the positions of parts shown in the drawings this pawl is held away from said bar by a flat face 25 which contacts 100 with the stem of the pawl. The operating lever is itself held in inoperative position by a spring pin 27 which engages a shallow socket 29 in the side of said lever. The double pawl 31 is fast to a bent rod 33 one 105 end of which forms a handle as shown in

Fig. 1. The upper point 131 of the double pawl serves, when in the position shown, to prevent the rack-bar from moving in either direction and is so held when the operating lever 17 is in raised position by a spring 35 which connects the handle portion of the rod 33 with a pin 37 carried by the operating lever 17. If now it is desired to operate the jack, the double pawl is rocked to bring the lower point 231 into engagement with the teeth 11, and the operating lever 17 is forced downwardly to cause the pawl 21 to engage one of the teeth 13 and force the rack bar downwardly. Further manipulation of the lever 17 will force the rack-bar downwardly by intermittent steps; and whenever the desired amount of downward movement has been imparted to the rack-bar, the lever 17 is raised into the position shown and the handle portion of the rod 33 raised and released, whereupon the parts will be held in the position shown. If now it is desired to raise the rack-bar the handle portion of the rod 33 is manipulated to bring the double pawl to neutral position, whereupon the rack-bar may be lifted to any desired position. Release of the double pawl 33 will then permit the spring 35 to throw the double pawl back into the position shown in Fig. 2 to hold the rack-bar from falling.

The holder for the veneered soles comprises a U-shaped frame 39. To the base of said frame is fastened a leaf spring 41, and upon the spring rests a support 43 for a pile of blanks, said support being attached, if desired, to one end of said leaf spring. Slidable upon the arms of the U is a clamping member 44 which comprises a rectangular frame and two eccentrics 45 carried thereby on rotatable studs 47, the direction of extent of greatest eccentricity being indicated by the dot and dash lines in Fig. 4. A spring 49 connects the eccentrics, as shown, and is of sufficient strength to prevent the clamping member from sliding down the uprights 39 under the influence of gravity. It will be noted, however, that the eccentrics are in effect a one-way clutch which permits the clamping member 44 to be pushed downwardly if sufficient force is applied but prevents it from being lifted. The studs 47 have square ends to receive socket wrenches for locking the member 44 more securely in adjusted position or if desired for unlocking it after it has been locked.

The operation of the machine is as follows: A plurality of veneered soles are piled in the holder, a short piece of board laid on the pile, and the clamp 44 pushed

down into contact with the board after which the holder is placed on the base 1. The operator then pushes down on the handle portion of the rod 33 and then manipulates the lever 17 to force the rack-bar 9 downwardly. When sufficient pressure has been applied in this manner to put the spring 41 to the desired degree of tension, the eccentrics 45 may be turned to lock the clamp 44 firmly in place. The lever 17 is then raised to the position shown in Figs. 1 and 3, the double pawl moved to neutral position, while the rack-bar is lifted, and then to the position shown in Fig. 2. The holder is then removed and put aside. It will be noted that the spring 41 is under tension and that, therefore, a steady pressure will be maintained on the veneered soles during the drying and setting process.

Although the invention has been described in connection with a particular machine it should be understood that the invention is not limited in the scope of its application to the particular machine shown and described.

Having thus described our invention, we claim as new and desire to secure by Letters Patent:

1. A machine of the class described having, in combination, means for supporting a pile of blanks, a spring, means for applying pressure to said blanks through said spring whereby said spring is compressed, and means for holding said spring compressed when the pressure applying means is removed.

2. A holder for a pile of blanks adapted to be placed in and removed from a press, having, in combination, a frame to receive the blanks, a clamping member adapted to receive the thrust of a pressure-applying member of the press and to be moved thereby along the frame to compress the pile of blanks, a spring through which the pressure is applied, and means for locking the clamping member in compressing position to maintain the pressure after the holder has been removed from the press.

3. A holder for a pile of blanks adapted to be placed in and removed from a press, having, in combination, a U-shaped frame, a spring connected with said frame, a support for the pile resting upon the spring, a clamping member slidable on the arms of the frame and adapted to receive the thrust of a pressure-applying member, and a one-way clutch connecting the clamping member and frame.

In testimony whereof we have signed our names to this specification.

JOSEPH A. McDONALD.
WILLIAM R. FORSYTH.
